POTTERY FABRICATING MACHINE

James A. Bower, Chester, W. Va., assignor to The Taylor, Smith & Taylor Company, East Liverpool, Ohio, a corporation of West Virginia

Original application March 1, 1945, Serial No. 580,401. Divided and this application April 9, 1947, Serial No. 740,360

8 Claims. (Cl. 198—221)

1

The invention relates to a pottery fabricating machine, and this application is a division of my application Serial No. 580,401, filed March 1, 1945, and now abandoned.

My application Serial No. 580,401 discloses a completely automatic and integrated machine for fabricating pottery of either the vitreous or semi-vitreous type, and which is particularly well adapted to carry out the invention described and claimed in my Patents Nos. 2,273,015 and 2,273,016, granted February 17, 1942.

In the machine disclosed in my application Serial No. 580,401, the molds are placed in trays and the trays are caused to travel step-by-step through the machine, and all operations necessary for complete fabrication of the ware, such as cleaning the molds, pouring the slip, opening and closing the molds, drying the ware, removing, fettling, inverting and stacking the ware, etc., are performed automatically.

The present application does not relate to the operations of cleaning the molds, pouring the slip, opening and closing the molds, drying the ware, removing, fettling, inverting and stacking the ware, but rather it relates to the construction of the machine itself, the mechanism for operating the machine, the means by which the trays are carried through the entire machine comprising a number of vertically spaced tracks, etc.; the construction and arrangement being such that all operations necessary to the complete fabrication of the ware may be performed during the passage of the molds through the machine.

Various objects and advantages of the invention will be apparent to those skilled in the art from the following description when taken in connection with the accompanying drawings, in which:

Figure 1 is a perspective view of the pottery machine with an intermediate part broken away;

Figure 2 is a side elevational view of the power end of the apparatus;

Figure 3 is a perspective view of the power end of the apparatus with the upper portions thereof broken away;

Figure 4 is a fragmentary perspective view, on an enlarged scale, of the power end of the apparatus;

Figure 5 is a perspective view of a portion of the opposite end of the apparatus with parts removed, for the sake of clearness, and showing on an enlarged scale the means for engaging and restraining the end trays of a series of mold trays;

Figures 6, 7, 8 and 9 are detail views of the

2

means for temporarily engaging and restricting the trays at the ends of each series of trays;

Figure 10 is a fragmentary perspective view of the mechanism for operating the vertical conveyor at the rear or power end of the apparatus;

Figure 11 is a fragmentary plan view of the gearing shown in Figure 10;

Figure 12 is a perspective view of a pair of hooks forming latching means for interlocking a tray on one of the vertical conveyors;

Figure 13 is a detail elevational view of the tray latch and associated mechanism for automatically releasing the same at the proper time; and

Figure 14 is a diagrammatic view of the hydraulic system for operating the weight and associated parts for causing the mold trays to travel through the apparatus in a substantial harmonic motion, step-by-step.

Before proceeding with a description of the details of construction and operation of the apparatus it is deemed desirable to describe in a general way both the structure and the main operational features of the machine as a whole.

As previously stated, the machine is designed for casting pottery and is entirely automatic including the initial step of filling the molds with slip and the final step of fettling the ware and placing it on a conveyor in stacks of proper height, ready for firing in the kiln.

The main frame of the apparatus as shown in Figure 1 comprises a track composed of ten vertically spaced track sections or guideways, hereinafter referred to as tracks, upon which mold-carrying trays, such as shown at the left of Figure 4, are pushed along in a step-by-step movement, so as to provide dwell points or stations, throughout the continued operation of the apparatus. As each tray reaches the end of a particular track, except the top one, it is moved upwardly to the next track, by vertically disposed conveyors at opposite ends of the machine. The entire period of movement and rest comprises less than ten seconds.

While there are ten vertically spaced tracks in the embodiment illustrated, it will be understood that the number of tracks depends on the space available. Thus the machine may be lengthened to reduce the number of tracks as desired, if sufficient space is available, and thereby reduce the number of times the trays must be transferred.

In the specific embodiment of the invention illustrated, a substantial simple harmonic step-

by-step movement is imparted to the trays by means of a heavily weighted pendulum operated by an hydraulic system, shown in Figure 14, which also operates the elevators at the opposite ends of the apparatus. The operation of the hydraulic system is controlled by electric circuits provided with safety switches to insure proper and timely functioning of the various mechanisms. These circuits form no part of the present invention, and illustration thereof is unnecessary.

There are six molds, such as shown at the left of Figure 4, mounted on each tray and each mold comprises upper and lower sections. At a certain stage of the process the upper mold sections are unlatched and removed from the lower mold sections and placed beside them on the tray.

The mold sections are assembled and latched together at the right of the lower or No. 1 track in Figure 1. The trays with the closed molds are then moved successively to the second or No. 2 track by a vertical conveyer at the right of Figure 1, where they are filled with measured quantities of slip. Thereafter the charged molds travel along tracks Nos. 2, 3, 4, 5, and 6, during which time substantial quantities of moisture in the slip is being absorbed by the walls of plaster-of-Paris molds or other porous molds. On the sixth track automatically operated mechanisms are provided for removing excess slip from the funnels of the molds and for unlatching and removing the upper mold sections. The fully formed and exposed ware is then automatically stamped with a trade-mark or the like and travels through an enclosed zone comprising a portion of track 6 and tracks Nos. 7, 8, 9, and 10, where heated air is directed on the ware to dissipate residual moisture therefrom. After leaving the drying zone the trays descend on the endless vertical conveyer at the left of Figure 1, where take-out mechanisms are provided for removing the ware from the molds, fettling the ware, inverting it and stacking it on a conveyer in the proper height stacks, ready for firing in the kiln. The trays of empty molds are then placed on the lowermost track and gradually moved in step-by-step fashion through a heating zone and to the mold assembling apparatus mentioned hereinbefore, at which point a repetition of the process is initiated. The various operations on the molds, such as filling, disassembling, drying, etc., are of course performed during the dwell periods of the molds in their travel through the machine. All the mechanism for performing all of the operations mentioned above is shown in my parent application, Serial No. 580,401. The present divisional application relates mainly to the machine itself, the mechanism for driving the machine, carrying the trays loaded with molds along the various tracks where the numerous operations are performed, the transfer of the trays from one track to another, etc., and hence only those parts which are pertinent to the subject-matter hereof, are described herein. And while these parts are described in considerable detail such detailed disclosure is intended as illustrative only and not in any limiting sense.

The trays are indicated by numeral 1, and as shown at the left of Figure 4 they are relatively long and narrow and are composed of longitudinal side bars 2 of angle formation which are united at their respective ends by the end bars 3. The bars 3 are slightly longer than the

width of the trays so as to provide end portions 4 which contact similar portions of adjacent trays when passing along the tracks of the apparatus and which also provide a slight space between the side bars of adjacent trays.

Each tray is designed to carry six molds through the apparatus, although it will be understood that this number may be increased or decreased as desired. The molds are composed of upper and lower sections 5 and 6 respectively, as shown at the left of Figure 4, where an upper mold section has been removed from a lower mold section and positioned beside it on the tray. The mold sections are in the form of metal rings of angular cross-section to which are molded sections 7 and 8 made of plaster-of-Paris or other porous material which form the mold cavity. Each of the upper mold sections is provided with a charging or filling funnel 20 which is permanently imbedded in the plaster-of-Paris and which opens into the interior of the mold. No further description of the molds is necessary herein, as the molds are the subject-matter of another divisional application Serial No. 740,105, filed April 8, 1947, and now Patent No. 2,526,993, granted October 24, 1950.

A description of the general framework of the apparatus, as disclosed mainly in Figures 1, 2 and 3, will now be given.

The foundation of the apparatus is preferably composed of a suitably prepared flooring 25 (Figure 2) on which certain of the vertical standards are supported. Concrete blocks or base members 26 are preferably provided at the power end of the apparatus for supporting the heavier parts of the mechanism.

Shallow wells 27 may be provided in the floor at opposite ends of the apparatus to permit the installation of the lower ends of the vertical conveyers or elevators, as will later appear.

Mounted on the blocks 26 are horizontal beams 28 from which are supported the oscillatably-mounted weight and related parts which function to impart the step-by-step movement to the trays and the molds carried thereby. Extending vertically from the blocks 26 are a plurality of standards 29, and together with similar standards 30 (Figure 1) based on the floor 25, provide supports for the horizontal beams 31.

There are twenty of the beams 31, ten on each side of the framework and they are arranged in horizontal pairs, spaced vertically, to provide ten trackways for the mold trays. Each beam has mounted thereon a series of rollers 32 on which the trays are caused to ride in their travel through the apparatus. As previously mentioned, the trays on each track are in contact with each other and the entire series on each track is caused to move forward one step at a time by a pusher bar provided for each track. Therefore, in order to prevent buckling of a series of trays as it is pushed along its track a plate 33 (Figure 5) is mounted on each beam and extends lengthwise thereof in overhanging relation to the rollers 32; the space between the plate and the series of rollers being only slightly greater than the thickness of the trays.

The ten vertically-spaced tracks along which the trays are pushed may be considered as numbered one to ten, and as so considered there are five pusher bars for moving the trays on tracks Nos. 1, 3, 5, 7 and 9 to the right (Figures 1 and 2), and five for moving the trays on tracks Nos. 2, 4, 6, 8 and 10 to the left. These pusher bars

are rather massive affairs and are substantially rectangular in form, comprising side bars 34 and cross bars 35. The side bars 34 are mounted to slide on rollers 36 supported on the standards 29 and 30 of the main frame, and rollers 37 (Figures 5) are also mounted on the standards to engage the outer sides of the bars and thus guide these members. The pusher bars of each series may be rigidly connected by vertical braces, if desired.

Each cross bar 35 of a pusher bar is provided with a pair of rigid lugs or fingers 38 adapted to engage the adjacent side of the end tray of the particular series and move the entire series through the distance of movement of the pusher bar. The pusher bars of tracks Nos. 1 and 2 are provided with extensions 39 and 40 on which are formed racks 41 and 42 which cooperate with pinions 43 mounted on a shaft 44. Rollers 45 and 46 may be mounted on the main frame to engage opposite sides of the racks to maintain them in proper relation to the pinions. Also fixed to the shaft 44 are pinions 47 cooperating with racks 48 carried by the piston rods 49 of hydraulic cylinders 50 and 50^a. These piston rods are formed with a reduced portion or extension 49^a providing a shoulder whereby certain switches, which form no part of the present invention, may be operated. The main operative force applied to the shaft 44 is a weight or pendulum bob 51 rigidly suspended from the shaft by arms 52. This weight may be formed of metal, concrete or the like and weighs several tons, although the exact weight will of course depend upon the number of trays, molds, etc., employed in the particular installation. Obviously, power in addition to the pendulum must be employed to maintain the apparatus in operation and this additional power may be in the form of a hydraulic system of which the cylinders 50 and 50^a form a part. It should be noted however that by use of the pendulum the power required for acceleration and deceleration of the mold trays neutralize each other, thus requiring the use of only sufficient power to move the load at a uniform continuous speed. The hydraulic system will be described hereinafter.

The series of trays on tracks Nos. 3 to 10 inclusive are operated simultaneously with the trays on tracks Nos. 1 and 2, and to this end the shaft 44 is provided with bell-crank levers 53 fixed to its opposite ends. One end of each of these levers is connected to vertically extending rods 54 on opposite sides of the machine. The pusher bars for tracks Nos. 3 to 10 are provided with racks 56 similar to those employed with the pusher bars for tracks Nos. 1 and 2, and pinions 57 are employed for causing adjacent pusher bars to operate in opposite directions. In order to operate the pinions 57, alternately plain and bell-crank levers 58 and 59 respectively may be connected with the pinions and with the operating bar 54, the opposite ends of the bell-crank levers being connected to the rod 55. The sole purpose of the rod 55 is to maintain the operating rod 54 in vertical position, and this is accomplished by the use of the bell-crank levers for connecting the rods at spaced points.

The movement of the molds through the apparatus is an intermittent one, there being a substantial simple harmonic movement of all of the molds simultaneously along the tracks, then a period of dwell, and then a repetition of the movement. A complete cycle of operations, that is, the period of movement and dwell, ordinarily

requires about ten seconds, but the timing of course may be varied as desired. The substantial harmonic movement is provided by the action of the pendulum 51-52 (Figures 3 and 14), and the pendulum is temporarily maintained at the limits of its swing, particularly the rear swing, by the cylinders 50-50^a. Also, in order to avoid accidents, and to sustain the pendulum when the machine shuts down, weight locks 60 are provided. There are two of these locks or supports for cooperation with the weight at the end of its rear stroke, and they are located adjacent the ends of the weight on opposite sides of the apparatus. The locks 60 are slidably mounted on

the main frame of the machine and are operated by hydraulic cylinders 61 (Figure 3), in timed relation with other parts of the apparatus, preferably by an electric circuit which forms no part of the present invention.

As the mold trays 1 reach the end of each of tracks Nos. 1 to 9 they are raised to the next track above, and from track No. 10 they are moved to a ware removal and finishing station and then to a firing kiln. To accomplish this step-by-step movement of the mold trays a vertical conveyer or elevator is provided at each end of the apparatus and each is operated in timed relation with the pusher bars, etc., by the hydraulic system heretofore referred to.

The structural details of the elevators and their related parts will now be described, but inasmuch as they are substantial duplicates a description of one of them will suffice, except as to certain variations in structure or operation.

Each elevator comprises a pair of endless sprocket chains 65 cooperating with upper and lower pairs of sprocket wheels 66 and 67 respectively (Figures 1 and 2), the latter being positioned in the wells 27 at the front and rear of the machine and the former being mounted on the main frame of the machine at points slightly higher than the uppermost track No. 10. A lower shaft of each elevator is also provided with a cam wheel 67^a (Figure 1) having four circumferentially spaced lobes for operating switches in an electric control system. Vertical guideways 68 are provided to prevent lateral movement of the chains 65.

Pivots attached to each pair of sprocket chains is a uniformly spaced series of shelves for supporting the trays 1. These shelves, shown on an enlarged scale in Figure 12, are spaced along the chains at a distance corresponding with the spacing of tracks Nos. 1 and 2, or 3 and 4, etc., and the chains of course are spaced apart a distance corresponding substantially to the length of the mold trays. Each shelf comprises a pair of links or hangers 69, one pivoted to each chain, and rigidly connected to each other by a cross bar 70. Rigidly connected to each hanger is a shelf section 71. Each pair of chains of an elevator is operated in a direction which will cause the flight nearest the tracks to move upwardly and the remote flight to move downwardly.

The mechanism for operating the elevator at the right hand end of Figure 1 is shown in detail in Figures 10 and 11, and is identical with the mechanism for operating the elevator at the power end of the apparatus, except that the latter has no brake release, as will later appear. This driving mechanism will now be described.

Suitably supported on the main frame of the apparatus adjacent the top of the elevator is a base plate 75 (Figure 10) on which is rotatably mounted a pinion 76. The shaft of pinion 76

is provided with a crank-arm 77, the free end thereof being pivotally connected to an arm 78. Fixed to the shaft of the adjacent sprocket wheel 66 is a gear wheel 79 to one face of which are attached four uniformly spaced pins or lugs 80 adapted to cooperate with the arm 78. For this purpose the arm is formed with a reduced portion at its end to provide a pin engaging shoulder 81. Movement of the arm 78 to the right (Figure 10) will impart a rotary movement to the sprocket 76 and thus cause the elevator to operate. Movement of arm 78 to the left will have no effect on the sprocket wheel, but it will be noted that the arm is of such length that it will remain supported by one of the pins on its retrograde movement. Oscillation of the pinion 76 and crank-arm 77 is obtained by means of a hydraulic cylinder 82 and a rack 83 connected to the piston rod of the cylinder.

The length of stroke of cylinder 82 is such as will impart to the elevator a movement corresponding to the distance between tracks Nos. 1 and 2, etc. Necessary adjustments may of course be made in the stroke of the cylinder or in the connection between the crank-arm 77 and arm 78, so as to provide the desired flexibility of action required to bring the mold trays and shelves into alignment with the various tracks.

For the purpose of maintaining the elevator stationary after each operation a brake has been provided. In the present construction the brake is in the form of a brake drum 84 fixed to a shaft 85 which also carries a spur gear 86 meshing with gear wheel 79 secured to the sprocket shaft. Co-operating with brake drum 84 is a brake shoe 87 fixed to the underside of a pivoted arm 88. A weight 89 is secured to the free end of arm 88 and provides the necessary frictional contact between the braking elements 84 and 87. Release of the brake mechanism is obtained by means of a hydraulic cylinder 90, and it will be understood that this cylinder as well as cylinder 82, mentioned above, are operated in timed relation with other parts of the mechanism.

Mounted on the exterior face of the sprocket wheel 66 on the opposite end of the shaft carrying the gear wheel 79 are four pins 91 spaced in the same manner as the pins 80 mentioned above. The pins 91 function to close a switch in an electric circuit to indicate that the elevators are in the proper position with the trays level with the tracks. A pawl or latch 92, with a rounded nose 93, is provided to engage with rounded notches between the teeth of one of the sprocket wheels; a weight 94 maintaining the nose in engagement with the procket wheel. The purpose of latch 92 is to prevent movement of the elevator if the brake should fail.

The driving mechanism for the elevator at the power end of the apparatus is substantially identical with that just described, except that no means is provided for releasing the brake. This is due to the fact that the elevator at the power end of the apparatus is more nearly in equilibrium by reason of the presence of trays on both its upwardly moving and downwardly moving flights, whereas, the other elevator supports trays on its upwardly moving flight only, as will appear hereinafter.

The details of the driving mechanism for the elevators has been described at considerable length, but it is intended that the disclosure be considered as illustrative rather than in a limiting sense.

As indicated on the drawings, the shelves 71

are provided with no flanges to prevent lateral movement of the trays 1 due to vibrations or jarring of the machine, etc. Moreover, such confinement of the trays would be impossible due to the fact that they must be pushed off and on the elevators, by the pusher bars 35, when being transferred from one track to another. Accordingly, automatically releasable interlocking means has been provided for preventing accidental movement or dislodgement of the trays from the elevator shelves. Such means is shown in detail in Figures 12 and 13, and comprises a shaft 95 rotatably mounted in bearings 96 on the shelf 71. A pair of outwardly directed fingers 97 are formed on the shaft 95 and are spaced longitudinally of the shaft a distance corresponding substantially to the width of the space between the side walls of a tray 1. A coil spring 98 serves to bias the shaft in a direction to cause the fingers 97 to interlock with the corners of the tray. To release the tray, a cam 99 is fixed to an end of shaft 95 and is adapted to engage a lock release bar 100, thereby rotating the shaft 95 against the tension of spring 98 and depressing the fingers 97 to a position below the tray 1. It will be understood of course that the length and position of the release bar 100 is such that the fingers 97 are in operative position when the elevators are moving, and are in inoperative position when the elevators are stationary, thereby permitting the loading or unloading of the trays onto and off of the elevators.

It is also essential that the trays 1 be accurately positioned on the elevator shelves when reaching each transfer position so as to prevent accidental engagement with the pusher bars 35 and other parts of the apparatus. To this end, vertically extending guide bars 101 (Figures 5 and 9) are provided. These bars are inclined towards each other at their upper ends, as indicated by numeral 102, and serve to insure the exact positioning of the trays as they arrive at the various stations for removal onto the several tracks.

Upon the movement of a mold tray from an elevator shelf onto a track as by operation of a pusher bar 35, it is desirable that means be provided for temporarily holding the tray in its new position until such time as it is moved forwardly by the next tray being pushed off the elevator onto the track at the next operation of the apparatus; otherwise there is the liability that the tray may be jarred backwardly off the track or at least into the line of movement of the elevator, thereby causing considerable damage and disruption of operations. This function is provided by means of a pair of pivoted latches adjacent the rear end of each track, operated by the respective pusher bar; one latch being mounted at each side of the track.

These latches are shown in detail in Figures 6 to 9 inclusive, and consist primarily of a shaft 105 rotatably mounted in a bearing 106 on each side of the main frame of the machine, and provided with locking fingers 107 on their inner ends for engaging a tray 1, and an operating arm 108 on their outer ends for cooperation with suitable mechanism depending from each side arm of the pusher bars. The operating means for the latches comprises a rigid arm or plate 110 extending downwardly from each arm 34 of a pusher bar 35 and provided with a spring-pressed plate 111 facing toward the operative end of the pusher bar. A cam member 112 in the form of a rod provided with an offset portion 113, has one end secured to the pusher bar and its opposite end to

the lower end of the plate 110. The arm 108 of the latch is in the path of movement of plate 111 and cam 113 as the pusher bar moves back and forth in its operations of moving trays from the elevator to the particular track in conjunction with which it operates. As will be noted from an inspection of Figures 7, 8 and 9, the arm 108 of the latch rides up on the rod 112 shortly after the pusher bar initiates its transfer of a tray from the elevator to a track, thereby releasing the tray previously moved forward from the elevator, and maintaining the locking fingers depressed until such time as the pusher bar approaches the limit of its return movement. In this latter position the arm 108 rides down the cam 113 and is engaged by the spring plate 111 which causes the finger 107 to engage the inner side of the wall of the tray just placed on the track, and maintains the tray against accidental displacement until the pusher bar is again operated. This operation of the fingers 107 also projects the tray against the previously loaded trays and tends to take up any slack in the series of trays, which may have been caused by jarring or the like created by action of the pusher bars. The dotted line positions shown in Figure 9 indicate the positions of the several parts at the time the fingers 107 first engage the tray.

In the course of pushing a mold tray from an elevator shelf onto a track it will be understood that the whole line of trays on the track is moved forwardly one step and that the foremost tray is pushed off the track onto the elevator at the far end of the track. Accordingly, it is necessary that means be provided to control the movement of the tray leaving the track so that it will be properly placed on the elevator shelf, and will not prematurely reach the line of elevator movement. Also it is desirable that the entire line of trays be compacted prior to the initiation of the forward stroke of the pusher bar. For this purpose each pusher bar is provided with a pair of hydraulically-operated levers or hooks at its remote end, one on each side of the pusher bar frame. These levers also serve in conjunction with the pendulum to apply the decelerating force of the pendulum to the tray lines.

The sequence of operations of the hooks is shown in Figures 7 and 8, and the construction thereof is shown in Figure 5. Each hook comprises a lever 115 pivoted on a plate carried by the pusher frame and provided with a roller 116 mounted on its free end. The opposite end of the lever is pivotally connected to the piston rod of a hydraulic cylinder 117, which latter is mounted on a bracket fixed to the frame of the particular pusher bar. The valve controlling the admission of oil or the like to cylinder 117 is operated by the timing drum of the electric circuit.

In Figure 8, the pusher bar is shown in its retracted position on each of two tracks and each is ready to push a tray onto its track as soon as the tray is brought into horizontal alignment with the track by the elevator. Just prior to the forward movement of the pusher bar the cylinder 117 will operate to move the lever 115 about its pivot and bring the roller 116 into engagement with the inner wall of the end tray. The lever is operated with sufficient force to take up any slack in the line of trays, the tray at the opposite end of the series being held against movement by the fingers 107 heretofore described. It will thus be seen that the entire series of trays is clamped between the pair of hooks at the

5 forward end of the series and the pair of fingers at the rear end of the series, and that buckling of the trays is prevented by the plates 37 which are fixed to the main frame of the apparatus and overhang the ends of the trays. With the series of trays thus encompassed and clamped together the pusher bar 35 moves it forwardly as a unit, removing a tray from the adjacent elevator onto the track and removing the remote tray of the series from the track onto the remote elevator. This latter condition is shown in Figure 7, and the hooks 115 have been raised so as to permit the pusher bar to return to its initial position. When the pusher bar reaches its rear-most position the lever arm 108 will be engaged by the spring plate 111 so as to raise the fingers 107 and lock the tray which has just been moved onto the track.

20 The mechanisms for moving the trays 1 in their general course through the pottery machine have been described, and I shall now describe that part of the hydraulic system which relates directly to the propulsion of the trays through the apparatus, namely, that part of the system 25 which operates the pusher bars and the elevators at the opposite ends of the apparatus.

As heretofore mentioned, the main source of power for operating the several pusher bars is the weighed pendulum 51-52 which functions to provide a slow start and stop to the lines of trays and a relatively rapid movement between the start and stop; the pendulum being momentarily halted at the end of its rear swing to prolong the interval of time during which various operations are performed on the molds, ware, etc., and to provide time for movement of the elevators.

Also, as heretofore mentioned, the pendulum is given a slight boost near the end of each swing so as to carry the weight somewhat beyond the ends of the normal path of its swing. The capacity of the cylinders necessary to provide the desired boost to the weight is such however that it is difficult to provide the necessary flow of 45 fluid to cause the pistons to keep pace with the pendulum, unless excessively large pumps are used. To avoid this the piston rods 49, as indicated at 49^a, are extended into cylinders 120 and 120^a of smaller diameter, which are connected into the hydraulic system. These latter cylinders have a smaller capacity than cylinders 50-50^a and are capable of causing the piston rods to keep up with and apply some little force to the pendulum. By-passes 121 and 121^a and 55 by-pass valves 122 and 122^a are provided for the cylinders 50-50^a, and it will be apparent that when these valves are opened, as is the case when cylinders 120-120^a are operating the larger pistons, the fluid will flow from one end of the cylinder to the other, thereby avoiding any drag on the pendulum and at the same time maintaining cylinders 50 and 50^a in condition to give the desired boost to the pendulum when the valves in the system are operated to inject fluid 60 pressure behind the pistons in cylinders 50-50^a.

The supply tank of the system is indicated by the numeral 123, and the fluid employed is preferably oil. From the tank 123 a line A, with suitable branches, leads to pumps B, C, and D operated by a motor M. And it should here be noted that the pump D is hooked up with the two pumps B merely for the purpose of increasing the capacity of these pumps. As indicated on Figure 14, the pumps C are used in conjunction with the elevator-operating cylin-

11

ders 62 at the opposite ends of the apparatus. A pipe line E connects with the pumps B, and with this line is connected line F which leads to the rear ends of cylinders 120 and 120^a. A pipe line G leads to the rear ends of main cylinders 50—50^a, and a line H leads to the forward ends of these cylinders. Connected with the line H is a line I which connects with line J leading to the forward ends of cylinders 120 and 120^a. As shown in the drawings, various check valves 124, arranged to open and close in the proper direction, are mounted in the several pipe lines. Also mounted in the system is the main pump 4-way valve 125, controlled by an electric system. Also connected in the pipe lines are relief valves 126, stop valves 127 and 127' (solenoid operated), a pump unloader or dump valve 128 (solenoid operated), retarder valve 129 (solenoid operated) and small pump C diverter valve 130, which is also operated by a solenoid. The function of these several valves in the operation of the hydraulic system relating to the pusher bars, etc., will now be described.

Assuming the pendulum 51 is ready to begin its forward swing, the weight locks 60 are automatically withdrawn from the path of the pendulum, the valve 125 is opened and stop valve 127 for the rear ends of cylinders 50—50^a, is closed, and the stop valve 127' to the opposite ends of these cylinders is opened; fluid pressure therefore travels from line E to line F to the rear ends of auxiliary cylinders 120—120^a. The by-pass valves 122 and 122^a are now opened by the operation of solenoids, to allow the oil to be transferred from the front to the rear ends of the main cylinders. The weight 51 thus swings forward, aided to some extent by the impulse from cylinders 120—120^a. Shortly before the weight reaches the extreme end of its forward swing the by-pass valves are closed, and at this time the stop valve 127 is opened and pressure is applied to the rear ends of cylinders 50 and 50^a as well as to the cylinders 120—120^a and the weight is "pumped up" to its proper destination. Fluid in the forward ends of the main cylinders is relieved through pipe H and its check valve 124 through 4-way valve 125 to the tank 123, and in order to prevent the pistons from hitting the ends of their cylinders too violently the retarder valve 129 is provided on the pressure side of the pumps to momentarily bleed off some of the pressure being directed to the cylinders. This valve of course functions on both the forward and reverse swings of the pendulum. During the application of pressure to the rear ends of the auxiliary cylinders, the fluid in their forward ends is relieved through pipe line J, valve 125 to the return line and supply tank 123.

The dump valve or pump unloader valve 128 is closed during the first five seconds of a cycle of operation, namely, during the forward and rearward swing of the pendulum, and is then opened.

At the termination of the forward stroke of the pendulum the 4-way valve 125 is closed or put in neutral position, and the apparatus is ready to begin the reverse movement to bring the pusher bars 35 into position for the next movement of the mold trays.

In this reverse movement, the 4-way valve 125 is opened, stop valve 127' is closed, and stop valve 127 is opened; fluid pressure therefore travels from line E to line J to the forward ends of auxiliary cylinders 120—120^a. The by-pass valves 122 and 122^a are now opened to allow the

12

oil to be transferred from the rear to the front ends of the main cylinders. The weight 51 thus swings rearwardly, aided by the impulse from cylinders 120—120^a. Shortly before the weight reaches the extreme end of its rearward swing the by-pass valves are closed, and at this time the stop valve 127' is opened and pressure is applied to the forward ends of the main cylinders as well as the auxiliary cylinders, and the weight is "pumped up" to its proper position at the termination of the rearward swing. Fluid in the rear ends of the main cylinders is relieved through pipe G and its check valve 124 and as in the forward swing the retarder valve 129 serves to slow down the movement of the pistons. During the application of pressure to the forward ends of the auxiliary cylinders, the fluid in their rear ends is relieved through pipe F, valve 125, and the return pipe to the supply tank 123.

At the termination of the rearward stroke of the pendulum the 4-way valve is closed or put in neutral position, and the weight is maintained at the limit of its rearward swing for about five seconds.

The function of the small pump (C) diverter valve 130 is to divert the flow of pressure from this pump to the main pump lines during the interval that the elevator at the remote end of the apparatus is at rest. It might also be mentioned that the four parallel pipes which are connected to the "return" line just below the tank and lead to the opposite ends of the several cylinders are provided so that in the event power should be shut off, for any reason, during a swing of the pendulum, pressure fluid can be drawn into the cylinders from the low pressure side of the system, by suction created by the pistons, thereby avoiding uncontrolled swinging movements of the pendulum.

In the course of movement of the trays through the machine the molds must be cleaned and then dusted with powder such as lamp black or the like, and the molds must be closed and filled. After a portion of the moisture has been absorbed by the plaster-of-Paris of the molds, the mold funnels are cleaned, the molds are then opened and a trade-mark stamped on the ware; thereafter jets of warm air are projected directly onto the ware, and the ware is then removed from the molds, and fettled, inverted, and stacked, and removed to a firing kiln. The molds must then be again cleaned and the entire process repeated.

All of these steps of the process are performed automatically by various work units which are incorporated in the machine and timed to operate in the desired sequence. These various work units are not described herein as they are the subject-matter of other divisional applications or of my parent application Serial No. 580,401. The present invention is concerned largely with the manner of operating the machine to get the molds therethrough in a way that permits the various operations to be performed on the molds. It is believed the apparatus and its mode of operation will be fully understood from the foregoing description, and therefore only a very general outline of the operation will be given below.

When the stops 60 are withdrawn the weight 51 and the pendulum will swing forwardly, being aided by the hydraulic system, as previously mentioned. This forward movement of the pendulum will cause one operative stroke of each

of the ten pusher bars 35. The pendulum then immediately returns to its original position, thus resetting all of the pusher bars in preparation for another operative stroke thereof. In this forward movement of the pusher bars a tray was moved from the elevators at opposite ends of the machine, onto each of the ten tracks, and as each tray was moved onto its track it caused a tray to be moved from the far end of that particular track onto an elevator. The pusher bars remain in their retracted position for about five seconds, and during this period the two elevators, at opposite ends of the apparatus, will move the various trays, which have just been placed thereon, to the next track level, ready to be placed thereon by the next operative movement of the pusher bars. In this movement of the pusher bars a tray was moved from the elevators onto each of the tracks, and a tray was moved from the far end of each track onto the elevators.

Of course, timing mechanism and safety mechanism are employed in order to insure the proper operation of the various parts, and to cause the entire machine to shut down in the event that the proper sequence of events is for any reason disrupted. Neither the timing mechanism nor the safety mechanism form a part of the present invention, and hence a disclosure thereof is unnecessary, and particularly so as the electric timing and control systems comprising interlocking circuits and switches operated by moving parts of a machine, are more or less conventional.

In accordance with the patent statutes I have described what I now believe to be the preferred form of the invention but inasmuch as various changes and modifications may be made in the construction without departing from the spirit of the invention, it is intended that all such changes and modifications be included within the scope of the appended claims.

What I claim is:

1. In a pottery fabricating machine, a plurality of trays for supporting molds, a track upon which said trays are slidable, intermittently operated means at one end of the track for pushing the trays along the track in a step-by-step movement, and a cylinder-operated lever at the opposite end of the track for engaging the tray at that end of the track and compacting the line of trays.

2. In a pottery fabricating machine a plurality of trays for supporting molds, a track upon which said trays are slidable, intermittently operated means at one end of the track for pushing the line of trays along the track in a step-by-step movement, a cylinder-operated lever at the opposite end of the track for engaging the tray at that end of the track and compacting the line of trays at about the time they are to be moved forwardly, and a latch for engaging the last of said line of trays after it is so moved so as to prevent backward movement thereof.

3. In a pottery fabricating machine a plurality of trays for supporting molds, a track upon which said trays are slidable, an intermittently operated pusher bar at one end of the track for pushing the line of trays along the track in a step-by-step movement, a latch for engaging the last of said line of trays after it is moved, and a plate carried by the pusher bar to press the latch against said tray when the pusher bar is retracted to operative position.

4. In a pottery fabricating machine a plural-

ity of trays for supporting molds, a track upon which said trays are slidable, an intermittently operated pusher member for pushing the line of trays along the track in step-by-step movement, and a cylinder-operated lever on the remote end of the pusher member to engage the adjacent tray and compact the line of trays prior to a forward movement of the pusher member.

5. In a pottery fabricating machine, a plurality of trays for supporting molds, a track upon which said trays are slidable, an intermittently operated member for pushing the line of trays along the track in step-by-step movement, said member including a substantially rectangular frame extending the length of the track, a pusher bar on one end of the frame for pushing the line of trays, and a cylinder-operated lever on the first tray and compacting the line of trays prior to the operation of the pusher member.

6. In a pottery fabricating machine a plurality of trays for supporting molds, a track upon which said trays are movable, a pusher bar for moving the trays along the track in a step-by-step movement, a shaft, an operative connection between said shaft and the pusher bar, a pendulum connected with said shaft for oscillating the same, and a hydraulic control system operatively connected with the pendulum.

7. In a pottery fabricating machine a plurality of trays for supporting molds, a track upon which said trays are movable, a pusher bar for moving the trays along the track in a step-by-step movement, a shaft, an operative connection between said shaft and the pusher bar, a pendulum connected with the shaft for oscillating the same, a hydraulic control system operatively connected with said pendulum, and a lock automatically positioned immediately below the pendulum at the end of each of its movements for supporting the same under certain conditions.

8. In a pottery fabricating machine a plurality of trays for supporting molds, a track upon which said trays are movable, a pusher bar for moving the trays along the track in a step-by-step movement, a shaft, an operative connection between said shaft and the pusher bar, a pendulum connected with the shaft for oscillating the same, a hydraulic system including a pair of cylinders and pistons and a common piston rod, said piston rod being operatively connected to said pendulum, one of said cylinders and pistons being of sufficiently small diameter to cause the piston to apply force to the pendulum at the rapid portion of its swing, and the other cylinder and piston being sufficiently large in diameter to lift the pendulum to the limit of its amplitude of movement.
